US00D949515S

(12) United States Design Patent (10) Patent No.: US D949,515 S
(45) Date of Patent: * Apr. 26, 2022

(54) BRASSIERE

(71) Applicant: Textiles Swantex S.A., Bogotá (CO)
(72) Inventor: Jesus David Posada Martinez, Bogotá (CO)

() Term: 15 Years

(21) Appl. No.: 29/719,524

(22) Filed: Jan. 6, 2020

(30) Foreign Application Priority Data

Jul. 9, 2019 (CO) NC2019/0007349
(51) LOC (13) Cl. 02-01
(52) U.S. Cl. ..... USPC D2/708; D2/706
(58) Field of Classification Search ..... USPC D2/702, 703, 706-710, 718-727, 731, D2/737, 739
See application file for complete search history.
